CATCH FOR A LUGGAGE CASE OR SIMILAR ARTICLE

Willard G. Axtell, Denver, Colo., assignor to Shwayder Brothers, Inc., Denver, Colo., a corporation of Colorado

Application July 19, 1947, Serial No. 140,403

Term of patent 14 years

(Cl. D87—1)

To all whom it may concern:

Be it known that I, Willard G. Axtell, a citizen of the United States, residing at Denver, in the city and county of Denver and State of Colorado, have invented a new, original, and ornamental Design for a Catch for a Luggage Case or Similar Article, of which the following is a specification, reference being had to the accompanying drawing, forming a part thereof.

Figure 1 is a plan view of the catch embodying my new design.

Figure 2 is a side elevation of the catch.

Figure 3 is an end elevation of the catch taken at the left end of Fig. 2.

Figure 4 is an end elevation of the catch taken at the right end of Fig. 2.

The dominant feature of my design resides in the portion disclosed in full lines.

I claim:

The ornamental design for a catch for a luggage case or similar article, as shown and described.

WILLARD G. AXTELL.
